UNITED STATES PATENT OFFICE.

ARMAND H. PEYCKE, OF CHICAGO, ILLINOIS, ASSIGNOR TO AMERICAN STEEL FOUNDRIES, OF NEW YORK, N. Y., A CORPORATION OF NEW JERSEY.

SPRING-DAMPENER.

1,185,434.

Specification of Letters Patent. Patented May 30, 1916.

Application filed September 17, 1915. Serial No. 51,140.

To all whom it may concern:

Be it known that I, ARMAND H. PEYCKE, a citizen of the United States, and resident of Chicago, in the county of Cook and State 5 of Illinois, have invented certain new and useful Improvements in Spring-Dampeners, of which the following is a specification.

My invention relates to springs, and has particular reference to a novel spring dampener or spring control.

It has been found that the action of the springs which serve to resiliently support the bodies of railway cars is peculiar. For instance, it has been found that inequalities 15 of track or roadbed cause an initial actuation of the springs carried by the car truck, and that the deflections caused by such inequalities are cumulative, the up and down movement under the action of the springs 20 increasing progressively until the point is reached at which the springs are completely compressed and the vibration of the car body stopped thereby. This action is repeated many times in the travel of the car 25 and is deleterious not only to the springs but to the roadbed and the car. This has been sought to be overcome by the use of greater capacity springs, with the result that the required resiliency under light shocks is not 30 present. The desired result may, however, be secured by the use of a dampener or friction element in connection with each nest of springs.

The construction shown herein is intended 35 as an improvement on the construction claimed in my co-pending application, Serial No. 42,693, filed July 30, 1915, Patent No. 1,169,863 of February 1, 1916.

The invention will be more readily understood by reference to the accompanying drawings, wherein—

Figure 1 is a vertical section through a dampener constructed in accordance with my invention, and Fig. 2 is a transverse section through the construction shown in 45 Fig. 1.

In the drawings, it will be seen that I provide upper and lower plates 10, 11, respectively, between which are confined a plurality of springs (not shown) which serve to support certain elements of a car. Located 50 axially of the nest of springs is a sleeve, 12,

shown in this instance as of rectangular cross section, the flanged upper end 13 of which is suitably secured to the top plate 55 10. Secured to the lower plate 11 are two friction elements 14, 15, each of which is triangular in cross section, both of which when united forming a square of the outline of the sleeve 12, and adapted to occupy 60 the space interiorly of the sleeve. The inside portions of the members 14, 15 are recessed to accommodate springs 16, 17, 18, 19, the springs 16, 18 exerting their force at an angle of 90° to the springs 17, 19. Thus the 65 members 14, 15 are forced outwardly against the inner walls of the sleeve 12, thereby inducing a high frictional resistance to the up and down movement of the plates 10, 11 under the action of the springs confined 70 therebetween. The result of such construction is that all teetering or cumulative compression of the springs is avoided.

Obviously other forms of the construction may be evolved, and such forms as are within 75 the scope of my claims I consider within the spirit of my invention.

I claim:

1. In a spring dampener, the combination of upper and lower plates, a rectangular barrel secured to said upper plate, a pair of rectangular friction members secured to said lower plate and interfiting with said barrel, and two springs located interiorly of said friction members and tending to exert their 80 force to spread said rectangular members, one spring exerting its force at right angles to the other thereof, substantially as described.

2. In a spring dampener, the combination 90 of upper and lower plates, a rectangular barrel secured to said upper plate, a pair of segmental members secured to said lower plate, and two pairs of springs located interiorly 95 of said segmental members, one pair of said springs exerting its force at right angles to the other pair of said springs, substantially as described.

Signed at Chicago, Illinois, this 14th day of Sept., 1915.

ARMAND H. PEYCKE.
